UNITED STATES PATENT OFFICE.

FREDERIC CONDÉ, OF OSWEGO, NEW YORK.

DESIGN FOR KNITTED FABRIC.

No. 37,565.

Specification for Design.

Patented Sept. 26, 1905.

Application filed July 10, 1905. Serial No. 269,138. Term of patent 3½ years.

To all whom it may concern:

Be it known that I, FREDERIC CONDÉ, a citizen of the United States, residing at Oswego, county of Oswego, State of New York, have invented a new, original, and ornamental Design for Knitted Fabric, of which the following is a specification.

The design is illustrated in the accompanying drawing, in which the figure is an elevation of a portion of a knitted fabric, showing my new design.

I claim—

The ornamental design for a knitted fabric; substantially as shown.

FREDERIC CONDÉ.
